ATTORNEY

UNITED STATES PATENT OFFICE.

HENRY DICKS, OF NEW YORK, N. Y., ASSIGNOR TO THE CUTLER-HAMMER MFG. CO.,
OF MILWAUKEE, WISCONSIN, A CORPORATION OF WISCONSIN.

ELECTRIC HEATER.

1,374,639.

Specification of Letters Patent. Patented Apr. 12, 1921.

Application filed November 3, 1919. Serial No. 335,307.

To all whom it may concern:

Be it known that I, HENRY DICKS, a citizen of the United States, residing at New York, in the county of Bronx and State of New York, have invented new and useful Improvements in Electric Heaters, of which the following is a specification.

This invention relates to electric heaters.

An object of this invention is to provide an electric heater wherein the resistor when glowing is visible throughout practically its entire length.

Another object is to provide an electric heater having the resistor thereof so mounted that practically the entire surface of the resistor throughout its length is effective to furnish light.

Another object is to provide a simple electric heater of few parts easily and quickly assembled.

The electric heater embodying this invention is particularly useful when mounted in reflectors of radiant heaters but may be employed elsewhere.

An embodiment of this invention is illustrated in the accompanying drawings in which—

Figure 1 is a front elevation of a reflector in which the heater is mounted.

Fig. 2 is a top plan of the heater.

Fig. 3 is a view on line 3—3 of Fig. 2.

The heater comprises a resistor 5 arranged in a zigzag path, and extends around a plate 6 of mica or other transparent material.

The inner loops formed in the resistor by arranging the heater in a zigzag path overlie the insulating plate 6. The resistor is secured to the insulating plate by means of

40 rivets 7 passing through apertures in the insulating plate and through the inner loops of the resistor. The ends of the rivets are expanded to firmly clamp the resistor to the insulating plate at intervals.

The heater may be mounted in a reflector 10 by means of pins secured to each end of the insulating plate 6. These pins extend forwardly from the reflector 10 and support the heater which is thereby spaced a short distance from the surface of the reflector.

50 The ends of the resistor 5 may be connected with conductors 12 and 13 leading to a source of electric current.

The heater may be mounted in the reflector with the resistor 5 mounted upon the front or back of the insulating plate. As 55 illustrated, the resistor is mounted upon the front of this insulating plate. When the resistor is connected with the source of electric current and is glowing, practically the entire length of the resistor is plainly visible. 60 Since the resistor is mounted on a transparent support, the light emitted from the resistor may readily pass through the transparent support. It is then reflected by the surface of the reflector, thereby increasing 65 the amount of light furnished by the heater.

Obviously other structures may be devised which will embody the invention herein set forth.

What is claimed is:

1. An electric heater comprising a transparent insulating base and a resistor mounted thereon.

2. An electric heater comprising an insulating plate, a resistor arranged in a zig-zag path and formed about the margin of the insulating plate with inwardly extending loops of the resistor overlying the plate, and means for securing the resistor to the plate.

3. An electric heater comprising a transparent insulating plate, a resistor arranged in a zigzag path and formed about the margin of the plate with inwardly extending loops of the resistor overlying the plate, and means engaging some of the loops at the base thereof for fastening the resistor to the plate.

4. An electric heater comprising a transparent insulating plate, a resistor arranged in a zigzag path and formed about the margin of the plate with inwardly extending loops of the resistor overlying the plate, and rivets engaging some of the loops at the base thereof for fastening the resistor to the plate.

5. An electric heater comprising a transparent insulating plate, a resistor arranged in a zigzag path overlying the plate, and means engaging the resistor at intervals for attaching the resistor to the plate.

In witness whereof, I have hereunto subscribed my name.

HENRY DICKS.
